INFLATABLE KITE

Louis Lawrence Laske, Grayslake, Ill., assignor to Vonco Products, Inc., Lake Villa, Ill.

Filed May 13, 1974, Ser. No. 469,066

Term of patent 14 years

Int. Cl. D21—01

U.S. Cl. D34—15 AF

FIG. 1 is a top plan view of an inflatable kite showing my new design, the bottom being substantially similar thereto;

FIG. 2 is a right side elevational view thereof, the left side being a mirror image thereto;

FIG. 3 is a rear elevational view thereof.

I claim:

The ornamental design for an inflatable kite, substantially as shown and described.
